United States Patent Office.

JOSEPH PHILIPS AND DAVIS KEELEY, OF PHOENIXVILLE, PENNSYLVANIA.

Letters Patent No. 95,263, dated September 28, 1869.

IMPROVEMENT IN FURNACE-DOORS.

The Schedule referred to in these Letters Patent and making part of the same.

To all whom it may concern:

Be it known that we, JOSEPH PHILIPS, and DAVIS KEELEY, of Phoenixville, in the county of Chester, and the State of Pennsylvania, have invented a new and useful Improvement in Water-Doors for Furnaces; and we do hereby declare that the following is a full, clear, and exact description thereof, which will enable those skilled in the art to make and use the same, reference being had to the accompanying drawings, forming part of this specification.

This invention relates to a new and useful improvement in doors for puddling, blast, and other furnaces; and consists in producing a circulation of water in a serpentine channel through the door, by means of partitions, as will be hereinafter described.

In the accompanying drawing—

Figure 1 represents a side view of a door partly in section, constructed with a water-channel, according to our invention.

Figure 2 is a vertical section of fig. 1, through the line *xx*.

Similar letters of reference indicate corresponding parts.

This door is cast in a single piece, by so setting sand cores in the mould, that the iron partitions marked A will be left, the core-sand being afterward removed through apertures in the top of the door, which are closed with thumb-screw B.

It will be seen that by this arrangement of the partitions A, a serpentine or zigzag channel is made through the door.

The water is introduced through the pipe screwed into the projecting limb C of the door; it passes under the first partition, and over the second, and so on through the door, as indicated by the arrows, and is discharged through the aperture D in the projection E.

By this means the door may be kept cool, while by the rapid circulation produced, the water will not be so heated, after it is discharged, as to be unfit for cooling the tools of the workmen.

Having thus described our invention,

What we claim as new, and desire to secure by Letters Patent, is—

Producing a circulation of water through a furnace-door, by means of the partition A, substantially as described.

The above specification of our invention signed by us, this   day of   , 1869.

JOSEPH PHILIPS.
DAVIS KEELEY.
